UNITED STATES PATENT OFFICE.

HANS HOLZWARTH, OF HAMILTON, OHIO, ASSIGNOR TO THE HOOVEN, OWENS, RENTSCHLER COMPANY, OF HAMILTON, OHIO.

DYNAMO-ELECTRIC MACHINE.

SPECIFICATION forming part of Letters Patent No. 752,168, dated February 16, 1904.

Application filed November 21, 1903. Serial No. 182,057. (No model.)

To all whom it may concern:

Be it known that I, HANS HOLZWARTH, a citizen of Germany, residing in Hamilton, Butler county, Ohio, (post-office address, Hamilton, Ohio,) have invented certain new and useful Improvements in Dynamo-Electric Machines, of which the following is a specification.

This invention pertaining to dynamo-electric machines relates particularly to improvements in construction designed to enhance the carrying away of the heat due to Foucault currents. In the case of dynamos directly connected to steam-turbines the speed may become extraordinarily high and the radiating-surfaces small. Again, in any of the ordinary constructions looking to the ventilation of armatures there are angularly-moving ports or air-passages, and the movement of the walls of these ports through the air at the high speeds generally associated with the conditions referred to produce a great deal of noise and consume considerable power. The result of all this is that none of the ordinary ventilating systems have proven satisfactory in connection with dynamos directly connected with steam-turbines.

My present invention will be readily understood from the following description, taken in connection with the accompanying drawings, in which—

Figure 1 is a diametrical section of the armature of a dynamo-electric machine exemplifying my invention; and Fig. 2 an end view of the same, partly transverse section, in conjunction with a field-pole appearing in section in a plane at right angles to the axis of the armature.

In the drawings, 1 indicates the armature as a whole; 2, the armature-shaft; 3, the armature-heads; 4, the armature-laminations; 5, the tie-bolts serving to clamp the laminations between the armature-heads; 6, air-spaces left at intervals between contiguous laminations, the construction as thus far particularly referred to being not unusual; 7, an annular chamber formed around the shaft within the bore of most of the laminations, which bore is made larger than the shaft in order to produce the general chamber in question; 8, trans-

verse partitions disposed at intervals in the chamber referred to, these partitions extending from the shaft to the enlarged bore of the laminations, the result being that the chamber surrounding the shaft is divided into a succession of chambers, one for each of the air-spaces 6, the partitions 8 in question to be constructed in any appropriate manner, but preferably by one of the plans hereinafter to be described; 9, volute separators disposed in the air-spaces 6 and serving as spacing-pieces and serving also as vanes to facilitate the outward discharge of the air; 10, light metallic shells, hereinafter more fully described, which may be employed to serve as linings for the air-spaces 6 and as supports for the laminations; 11, an axial bore in the armature-shaft; 12, branches from this bore leading diagonally into the chambers 7; 13, an injector arranged to discharge cooling air or gas into the axial bore 11 of the shaft; 14, a conduit leading to the injector and adapted for connection with any appropriate source of supply of cooling air or gas under pressure.

In Fig. 1 I illustrate three of the air-spaces 6 to the right as being walled directly by the laminations separated at the air-space, the separators 9, that maintain the spaces and serve as air-vanes, being in the form of light channel-bars bent to form and riveted to the appropriate laminations. The partitions 8 appropriate to this construction may be obtained by simply carrying an appropriately-disposed group of the laminations inwardly clear to the shaft.

At the left of Fig. 1 I illustrate a construction which will be advantageous in some instances. In this case the air-spaces 6 instead of having their walls formed directly by the separated laminations are walled by light castings 10, having the form of parallel disks with the separating-vanes 9 cast with them. The disks have light shell hubs lining the enlarged ports of the laminations, and an inward annular projection extending inwardly from the end of the hub to the shaft forms a partition 8, separating the chambers 7.

The branch conduits 12, leading from the axial bore of the shaft to the chambers 7, have

a double advantage by reason of their angular disposition relative to the axis of the shaft. The angle is favorable to the movement of the air outwardly; but the main advantage is that 5 the shaft is less weakened than if these conduits were radial. This may not be apparent at first glance; but very little analysis will show that the amount of metal removed to form one of these conduits bears a certain proportion to the bulk of metal through which 10 the conduit is cut and that the proportion is very much less than if the conduit were radial, this being due to the fact that a greater amount of the length of the shaft becomes involved in 15 the course of a given one of these branch conduits. If one will assume a cross-sectional tube of a shaft with the branch conduit radial, it will become apparent that the branch conduit appears as extending entirely through the 20 shaft from bore to periphery, while if a cross-section be assumed through a shaft provided with the angular branch conduit the conduit appears merely as a small hole in the shaft eccentric to the axial bore, or if a section be 25 taken near an end of the branch conduit then the branch conduit appears as a notch in the annular portion of the shaft.

Under some circumstances it may not be necessary to provide for forcible injection of 30 air to the system, the centrifugal effect of the armature upon the air being sufficient; but where insufficient then the injector enforces a circulation of cooling air or gas, and conduit 14 may have connection with a blower or 35 any other appropriate fluid-forcing means.

It will be manifest not only that the provision is made for a superior circulation for the cooling medium, but that there are no external air-admission openings having paths of 40 motion. The axial inlet to the shaft is without motion through space, and the consequence is that the ventilating system is productive of no noise or special loss of power. The system is equally applicable to plain armatures and Pacinotti armatures, the former 45 type being shown in the illustration.

In some constructions of machines where the air-gap is very small I make special provision for getting rid of the air-discharge from 50 the air-spaces of the armature by causing it to pass outwardly through ventilating-apertures formed in the field-cores, which apertures may be varied in form and number. This general provision will be readily understood from Fig. 2, where 15 indicates the field-yoke, 16 a field-core, 17 a field-pole, and 18 the air-apertures through the core.

In connection with Fig. 1 attention is particularly called to the individuality of the 60 chambers 7, each of which is supplied independently with air from the axial bore of the shaft. If a continuous chamber instead of a succession of chambers were provided, then the air delivered from the axial bore of the

shaft would seek its main outlet through the first one of the air-spaces 6 and the result would be a deficiency in cooling air delivered to the remainder of the air-spaces. The present arrangement insures the delivery of air to all of the air-spaces of the armature. 7c

I claim as my invention—

1. In a dynamo-electric machine, the combination, substantially as set forth, of an armature having a series of ventilating-spaces leading from the shaft outwardly and having 75 an independent inner chamber for each of said ventilating-spaces, and an armature-shaft having an axial conduit and having independent branch conduits placing said axial conduit in communication with said inner chambers. 80

2. In a dynamo-electric machine, the combination, substantially as set forth, of an armature having a series of ventilating-spaces leading from the shaft outwardly and having 85 an independent inner chamber for each of said ventilating-spaces, an armature-shaft having an axial conduit and having independent branch conduits placing said axial conduit in communication with said inner chambers, and means for forcibly delivering a cooling medium to the axial bore of the shaft. 90

3. In a dynamo-electric machine, the combination, substantially as set forth, of an armature having a series of ventilating-spaces leading from the shaft outwardly and having 95 an independent inner chamber for each of said ventilating-spaces, an armature-shaft having an axial conduit and having independent branch conduits placing said axial conduit in communication with said inner chambers, said 100 branch conduits being arranged at an angle to the axis of the shaft.

4. In a dynamo-electric machine, the combination, substantially as set forth, of an armature-shaft having an axial conduit and having 105 branch conduits leading outwardly therefrom, a series of laminations carried by the shaft and forming the general body of the armature and separated at intervals to form ventilating air-spaces leading from the shaft 110 outwardly, and separators disposed within said air-spaces and formed of separated wall-disks with vanes between them and having shell-hubs engaging within enlarged ports of the laminations. 115

5. In a dynamo-electric machine, the combination, substantially as set forth, of an armature provided with a series of ventilating air-spaces leading from the shaft outwardly, an armature-shaft having an axial conduit and having branch conduits placing the same in communication with said ventilating-spaces, and a field-core having air-passages extending from its polar face outwardly. 120
